AGRICULTURAL IMPLEMENT

Algy J. Smith, Bloomfield, Conn.

Application December 24, 1931, Serial No. 583,018

9 Claims. (Cl. 97—65)

This invention relates to an agricultural implement and more particularly to a hoe structure and a blade therefor, although the principles may also be adapted to other uses in various tools or other devices.

One of the chief difficulties incident to the use of hoes and other similar devices, which in many cases are used in cutting weeds, turf or other matter, is that the blades of such devices rapidly become dull, so that they must either be sharpened at frequent intervals or used in their dull state and their utility proportionately impaired. This fault is so prevalent that the expression, "as dull as a hoe" has for many years been a notorious bromide.

Among the objects of the present invention, therefore, is to provide a device and a blade therefor of such character that wear will not in any way interfere with its continued usefulness, and more particularly in which the blade will be as sharp after long use as when new.

A further object of the invention is to provide an interchangeable blade of the character and for cooperation with a device as above set forth.

25 A further object of the invention is to provide a small, cheap and efficient implement of the character described.

Other objects and advantages of my present invention will be described in and become apparent from the following specification and appended claims when considered in connection with the accompanying drawing, in which:

Figure 1 is an elevation of one form of my device, the handle being foreshortened for convenience of illustration;

Fig. 2 is a view taken at right angles to that of Fig. 1, with parts broken away and in section;

Fig. 3 is an end elevation of the device as seen from the right of Fig. 1;

40 Fig. 4 is a section taken on the line 4—4 of Fig. 3, the handle being broken off for convenience of illustration; and

Fig. 5 is an elevation of a modified form of my invention, the view being similar to that of Fig. 1.

In order to provide a tool or implement of the type above referred to which will retain its sharpness after wear, I employ for a cutting blade a piece of suitable material such as spring steel 50 of such thinness that its sharpness is an inherent property of the thinness of the material itself rather than a result of a sharpening operation thereon. For this purpose sheet spring steel .008 to .015 inches in thickness has been found

55 to be effective. Such material, while having

the necessary sharpness and toughness to resist wear, does not normally have the inherent rigidity necessary for the uses to which devices of this character are put. It is necessary, therefore, that this rigidity be artificially imparted thereto. 60 For accomplishing this object, I may clamp a flat blade in a position such that it is flexed within or beyond the elastic limit of the blade material and in a direction substantially transverse of the direction of the normal working 65 force which would be applied to the implement, which direction is also substantially parallel to the cutting edge of the blade.

Another method of accomplishing the desired result is to use a blade of the same or similar 70 material to that above set forth which is given a preliminary curvature of a permanent nature which will not return to a flat form upon release from its clamping or holding means. Such a blade might be either a single curved or a corrugated piece of sheet metal. Both types of blades are to be considered within the purview 75 of my invention.

Thus, my invention comprehends the use of a 80 blade of such thinness and flexibility as not to be self-sustaining in use and the combination of such a blade with a suitable support by which the blade may be secured to a suitable handle or other carrier or support in such a position and manner as to have the necessary rigidity in use. 85

Turning now more particularly to the drawing, and particularly Figs. 1 to 4 thereof, I have chosen to illustrate my invention as embodied in a garden hoe having the usual handle 1 tapered somewhat at one end and provided with any desired type of connection with a blade-supporting member 2. As shown, these members are connected by the use of an intermediate member 3, which may be T-shaped and formed as illustrated by bending a piece of strip metal. The stem of the T extends 90 into a longitudinal bore 4 in the tapered end of the handle 1. Surrounding this tapered end is a ferrule 5, the ferrule, handle and intermediate member all being secured together in any desired manner as by a rivet 6 extending therethrough as 95 illustrated in Fig. 2. The intermediate member 3 and the supporting member 2 may be secured together in any desired manner, the one illustrated in the drawing being rivets 7, the ends of which opposite the handle 1 being countersunk so as to be flush with the outer surface of the member 2. 100

The member 2 is rigid and is provided with a convexly curved outer face, that is, the face opposite the handle. To this member and against 110

this face is clamped the flexible blade, which is of light spring steel or other suitable material having the desired characteristics as above set forth. For clamping the blade 8 to the member 2, I prefer 5 to employ a complementary clamping member 9, the parts being detachably secured together in any desired manner as by bolts 10 and nuts 11, the former passing through suitable apertures in the members 9 and 2 and either apertures or 10 notches in the blade 8, apertures being shown in the present instance.

While I have shown the blade clamped to the member 2 by the use of a complementary clamping member, it will be understood that this member 15 may in some instances be omitted, and also that the member 2 need not in some cases be as solid as is shown in the accompanying drawing, it being necessary only that some support be provided by which the blade may be held firm and 20 if necessary flexed to substantially the configuration shown.

Considering Figs. 1 to 4, it will be noted that the flexing of the blade is in a direction transverse to the direction of the application of force to 25 the implement, whether this force act vertically downward (considering Fig. 1) or in a direction parallel to the handle 1. Also the flexing or permanent curvature of the blade is substantially parallel to the cutting edge 12 of the blade 8. It 30 will be noted further from a consideration of these figures that the material of the blade is so flexible that the flexure of the blade at the mid portion adjacent to its connection with the handle is greater than at the cutting edges. Thus the 35 cutting edge 12 of the tool is more nearly similar in contour to older types of hoes and is usable, for example, where it is desired to cut turf along a straight line.

The embodiment of my invention shown in 40 Figs. 1 to 4 is a hoe wherein the blade is substantially perpendicular to the handle. For some persons or purposes, however, it may be desired to have the blade at other than a right angle, such a structure being shown in Fig. 5, and being 45 formed in the same manner as above described with the exception that the connection between the member 2 and the handle 1 is such as to provide for the desired oblique relationship between the parts. The form of the device shown in Figs. 50 1 to 4 has the advantage over the other form in that both edges 12 and 12' of the blade may be used interchangeably, thus providing, in effect, two tools, or a blade having a double life. The 55 form of Fig. 5 may also be used on either edge, but usually only for different purposes, although it may be especially useful for these particular purposes due to the difference in the angular position of the blade with respect to the handle when the tool is inverted.

While I have shown and described but two 60 mechanical embodiments of my invention, it will be understood that various changes may be made therein, and the several principles thereof may be adapted to various purposes. I do not wish 65 to be limited therefore, except by the scope of the appended claims, which are to be construed as broadly as the state of the prior art permits.

What I claim is:

1. An agricultural device, comprising a supporting member curved on its outer side in a direction substantially transverse to the direction of application of the working force, a flexible working blade, and means for securing said blade to the curved outer side of said supporting member and thereby flexing said blade to impart rigidity 70

thereto, said member being laterally substantially coextensive with said blade for imparting the necessary rigidity thereto when in use.

2. An agricultural device, comprising, a supporting member curved on its outer side in a direction substantially transverse to the direction of application of the working force, a complementary cap member, and a flexible working blade adapted to be secured between said members, whereby the transverse flexure of the blade imparts rigidity thereto, said members being laterally substantially coextensive with said blade for imparting the necessary rigidity thereto when in use. 80

3. An agricultural implement, comprising a handle, a blade support rigid therewith having a face for contact with the blade curved in a direction substantially transverse to the direction of application of the working force, a complementary cap of substantially the same width as said support, and a flexible working blade of substantially the same width as said support and said cap and adapted to be gripped between said support and said cap, whereby the transverse flexure 90 of the blade imparts rigidity thereto. 95

4. In an agricultural device, a curved working blade of insufficient rigidity to be self sustaining in use, and means substantially coextensive laterally with said blade to hold said blade with the curvature thereof in a direction substantially parallel to its cutting edge and thereby impart the required rigidity thereto. 100

5. In an agricultural device, a curved working blade of material of insufficient rigidity to be self sustaining in use, and means substantially coextensive laterally with said blade to support said blade in a position such that its curvature is substantially transverse to the direction of application of the working force, whereby it is rigid in use. 110

6. A hoe structure, comprising a handle member, a blade support secured thereto, a flexible blade of insufficient rigidity to be self sustaining in use, and means substantially coextensive laterally with said blade to secure an intermediate portion of said blade to said support and thereby to flex such portion in a direction substantially transverse of said handle and of the direction of application of the working force, whereby to 120 provide a double sided hoe, the blade of which is rigidified by flexure. 125

7. A hoe structure, comprising a handle member, a blade support secured thereto, a curved interchangeable working blade, and means including a clamping member substantially coextensive laterally with said blade for securing said blade to said support in such position that the curve of said blade is in a direction substantially parallel to its cutting edge. 130

8. A hoe structure, comprising a handle member, a blade support secured thereto and having an outer surface for engagement with a blade which is curved in an arc, the center and plane of curvature of which lie substantially on and 140 through the axis of said handle respectively, a flexible working blade, and means substantially coextensive laterally with said blade for securing said blade to said support and thereby flexing said blade to cause it to conform to the curve of said support, whereby to impart rigidity to said blade. 145

9. A hoe structure, comprising a handle, a support adapted to be secured thereto having a face remote from the handle curved in a substantially transverse direction, a flexible working blade 150

adapted to be secured to said support in a position such that its cutting edge is substantially parallel to but spaced a substantial distance from a plane passing midway through said support and including the radius of curvature of the curved face thereof, means substantially coextensive laterally with said blade for securing said blade to said support and for thereby flexing it into conformity with the curved face thereof, and means for securing said support to said handle in such a way that a perpendicular to said plane is at an acute angle with the axis of said handle. 80'
